TOWEL RING

Raymond U. H. Tegner, Rockford, Ill., assignor to
Amerock Corporation, Rockford, Ill.
Filed Jan. 10, 1972, Ser. No. 216,908

Term of patent 14 years

Int. Cl. D6—06

U.S. Cl. D6—99

FIG. 1 is a top plan view of a towel ring embodying my new design.

FIG. 2 is a front elevational view thereof.

FIG. 3 is a right side elevational view thereof.

FIG. 4 is a fragmentary sectional view taken along the line 4—4 in FIG. 2.

FIG. 5 is a sectional view taken along the line 5—5 in FIG. 2.

FIG. 6 is a sectional view taken along the line 6—6 in FIG. 2.

FIG. 7 is a sectional view taken along the line 7—7 in FIG. 2.

FIG. 8 is a sectional view taken along the line 8—8 in FIG. 2.

I claim:

The ornamental design for a towel ring, as shown.
